UNITED STATES PATENT OFFICE.

RYUJI SATO, OF NEW YORK, N. Y.

TOY AND GAME.

1,350,082.

Specification of Letters Patent. Patented Aug. 17, 1920.

Application filed September 16, 1919. Serial No. 324,134.

To all whom it may concern:

Be it known that I, RYUJI SATO, a subject of the Emperor of Japan, residing at New York, county of New York, and State of New York, have invented certain new and useful Improvements in Toys and Games, of which the following is a specification.

The present invention relates to improvements in amusement devices, and particularly to a ball throwing game with the main object in view to provide a device of this kind in which dexterity and sure aim on the part of the player is required, who throw balls with the intention to direct them through a certain opening, the approach to said opening being provided with means to deflect the course of the ball, means being provided to return the ball to the thrower whether it passes through said opening or is deflected from its course.

A preferred form of the invention has been described herein and shown in the accompanying drawings, in which:—

Figure 1, is a longitudinal sectional view 25 of the amusement device, taken on line 1—1 of Fig. 3.

Fig. 2, is a similar sectional view, but showing the ball releasing means in releasing position.

Fig. 3, is a plan view of the device.

Fig. 4, is a front elevation of the device.

Fig. 5, is a sectional view of the device taken on line 5—5 of Fig. 3.

Similar numerals of reference designate 35 like parts in all the views of the drawings.

My improved device comprises an inclined base plate 1, which is rigidly attached at opposite ends to support 2 and 3.

A foot-board 4 and a head-board 5 extend 40 across the ends of the base plate, the foot-board projecting only slightly above the base plate while the head-board projects a greater distance above its end of the base plate. A pair of side-boards 6 and 7 connect the foot-board and head-board.

Merging into said base plate 1, as shown at 8, and supported by the side walls 6 and 7 is a second plate 9 which has a greater inclination than the base plates and leads to 50 a bridging member 10, said member 10 being mounted upon a third plate 11, which is also supported by the side walls 6 and 7, and arranged parallel to the base plate 1, at a certain distance above the same.

Said plate 11, is of less length than the member 10 and leaves a transverse aperture

9^a, extending from side wall 6, to side wall 7 between itself and the plate 9. Aperture 9^a is normally closed at its bottom by means of a slidable door 9^b.

Extending fixedly between the side-boards 6 and 7 is a vertically arranged target 13, preferably having the representation of a face formed thereon as shown in Fig. 4, this target having directly above the upper surface of plate 11 an oblong aperture 14 representing the mouth of said face, wherein teeth-like obstructions 15 leave a center opening 16 large enough to permit a ball of select size to pass through. Between the target 13 and head-board 5 is a trap door 17, having a hollowed out upper surface 18, hinged to a supporting member 19, by means of a spring actuated hinge 20, which has the tendency to retain the trap door normally in a closed position, the upward movement of the trap door being limited by a stop 21.

The aforementioned slidable door 9^b, rests upon and is guided by means of rails 22 and 23, projecting from side walls 6 and 7, and retained normally in closed position by means of two coiled springs 24 and 25. This slidable door 9^b, as well as the trap door 17, are actuated and opened by means of two cords 26 and 27 which pass over grooved pulleys 28, 29, 30 and 31, and engage the respective doors as shown at 32 and 33. These cords lead outwardly through an opening in the side-board 6 and are attached to a ring 34.

The upper surface of the bridging member 11 is on a level with the bottom of the opening 16, in target 13, and is gradually reduced in its width toward said opening, so as to increase the difficulty of directing a ball into said opening.

Two vertical ribs 35 and 36, are further provided on plate 11, for the purpose of guiding balls, which do not pass through opening 16, into the aperture 9^a.

An opening 37 is provided in the lower end of plate 9 adjacent the side wall 7, this opening extending up the plate a sufficient distance to permit of balls passing down the base-plate therethrough. A diagonal rib 38 extends along the base-plate under plate 9, the lower end of this rib being adjacent the opening 37.

The operation of the device is as follows:

The player, standing in front of foot-board 4, throws or rolls a ball in the direction of the target, aiming at the center open-

ing 16, of the same. The thrown ball will pass first over the inclined plate 9, then over the bridging member 10, and if properly aimed, through opening 16, whereupon it will fall into the hollowed portion of the trap door 17, to be retained there.

Any ball missing said opening 16 will be deflected by target 13, rolling back over plate 11, and coming to a stop in aperture 10 in 9^a, where it will rest upon the slidable door 9^b.

By pulling the cords 26 and 27 both the slidable door 9^b, and the trap door 18 will be actuated and opened, whereupon the balls accumulated thereon will be released and fall upon the base plate 1, rolling out through the opening 37, toward which they will be guided by rail 38 and arriving finally at the front partition 4.

20 While a preferred form of my invention has been described and shown herein, it is obvious that modification in form and arrangement of parts can be made without departing from the spirit of my invention and 25 from the scope of the annexed claims.

I claim:

1. In an amusement device of the character described, the combination of a target having an oblong mouthlike slot, a larger 30 opening in said slot, an inclined ball runway leading to said target, said ball runway constituted of portions of varying incline, a narrow member leading toward the opening in said target, said member being 35 narrower toward the said target, an aperture at a certain distance in front of the target, a slidable door closing normally said aperture, means to open said slidable door, a trap door behind said target, means to operate said 40 trap door in coöperation with said slidable door, and a guiding member underneath the

ball runway leading to a ball delivery opening.

2. In an amusement device of the character described, the combination of a target 45 having an opening therein, a ball runway leading to said target, guiding means adapted to cause the thrown balls to return by gravity to the starting point of said runway, and separate releasable retaining 50 devices adapted to prevent access respectively to said guiding means of the balls passing through said opening and the balls failing to pass through said opening.

3. In an amusement device of the character described, the combination of a target having an opening therein, a ball runway leading to said target, guiding means adapted to cause the thrown balls to return by gravity to the starting point of said runway, and separate releasable retaining 60 devices adapted to prevent access respectively to said guiding means of the balls passing through said opening and the balls failing to pass through said opening, and a common operating means for releasing said retaining devices.

4. In an amusement device of the character described, the combination of a target having an opening therein, a ball runway 70 leading to said target, guiding means adapted to cause the thrown balls to return by gravity to the starting point of said runway, a pair of doors one in front and one in rear of said target and adapted to have 75 the thrown balls collect thereon, and means for moving said doors to cause the balls thereon to be discharged to the said guiding means.

In testimony whereof I have affixed my 80 signature.

RYUJI SATO.
